UNITED STATES PATENT OFFICE.

ALBERT TILT, OF NEW YORK, N. Y.

DESIGN FOR A LAPEL-RIBBON.

55,577.

Specification for Design.

Patented June 29, 1920.

Application filed September 24, 1919. Serial No. 326,084. Term of patent 7 years.

To all whom it may concern:

Be it known that I, ALBERT TILT, a citizen of the United States, residing at New York, borough of Manhattan, in the county and State of New York, have invented a new, original, and ornamental Design for a Lapel-Ribbon, of which the following is a specification, reference being had to the accompanying drawings, forming part thereof.

Fig. 2 is a side view thereof.

I claim:

The ornamental design for a lapel ribbon, as shown.

ALBERT TILT.
